DESIGN FOR A PINOCHLE PEGGING SCOREBOARD

Lewis E. Ruddock, Springfield, Mass.

Application August 21, 1944, Serial No. 114,950.

Term of patent 14 years

(Cl. D34—5)

To all whom it may concern:

Be it known that I, Lewis E. Ruddock, a citizen of the United States of America, residing at Springfield, in the county of Hampden and State of Massachusetts, have invented a new, original, and ornamental Design for a Pinochle Pegging Scoreboard, of which the following is a specification, reference being had to the accompanying drawing, forming a part thereof.

Fig. 1 is a plan view of a pinochle pegging scoreboard, showing my new design;

Fig. 2 is a side elevational view; and

Fig. 3 is an end elevational view thereof.

I claim:

The ornamental design for a pinochle pegging scoreboard, substantially as shown.

LEWIS E. RUDDOCK.
